CLAIM

The ornamental design for a wearable earpiece with speaker, as shown and described.

DESCRIPTION

FIG. 1 is a perspective elevational side view of a wearable electronic earpiece device, according to one embodiment; FIG. 2 is a perspective left side view of a wearable electronic earpiece from FIG. 1; FIG. 3 is a perspective right side view of the wearable electronic earpiece from FIG. 1; FIG. 4 is a front view of the wearable electronic earpiece from FIG. 1; FIG. 5 is a rear view of the wearable electronic earpiece from FIG. 1; FIG. 6 is a top view of the wearable electronic earpiece from FIG. 1; and FIG. 7 is a bottom view of the wearable electronic earpiece from FIG. 1.

FIG. 8 is an alternate side perspective view of a wearable earpiece with speaker of FIG. 1; FIG. 9 is an opposite side view thereof; and,

FIG. 10 is another side view thereof, the ear insert speaker detached from the earpiece is drawn in broken lines and forms no part of the claimed design.

The broken lines of the FIGURES depict environment; however, the broken lines form no part of the claimed design. Additionally, in some embodiments, line shading is meant to show contour of represented surfaces and not surface ornamentation.
